UNITED STATES PATENT OFFICE.

RICHARD WEBB BURNETT, OF MONTREAL, QUEBEC, CANADA.

CONVERTIBLE CAR.

1,201,690.

Specification of Letters Patent.

Patented Oct. 17, 1916.

Continuation in part of application Serial No. 671,144, filed January 15, 1912. This application filed July 26, 1913. Serial No. 781,349.

To all whom it may concern:

Be it known that I, RICHARD WEBB BURNETT, of the city of Montreal, in the Province of Quebec, Dominion of Canada, have invented certain new and useful Improvements in Convertible Cars; and I do hereby declare that the following is a full, clear, and exact description thereof.

My invention relates to that type of convertible car for carrying small freight capable of being dumped and larger freight not capable of being dumped and it has for its object to simplify the construction of convertible cars of this type.

My invention relates particularly to the type of convertible car having a floor made up of displaceable members serving in one position as a horizontal flush floor and in another position as floors of a series of distinct hoppers.

The invention consists of means for supporting the floor members in horizontal position and means for supporting them in position constituting the hopper bottoms; the means for supporting them in horizontal position including devices serving as doors for controlling the discharge from the hoppers presented when the floor members are lowered; and the invention further consists of means located at the hinge-sides of the floor members and adapted to at all times bear or rub against a fixed part of the car frame for preventing leakage through the hinge of each floor member and for cushioning the fall of the floor member when dropped from the horizontal to the hopper bottom position.

For full comprehension, however, of my invention reference must be had to the accompanying drawings forming a part of this specification in which similar reference characters indicate the same parts, and wherein:

Figure 1 is a transverse vertical sectional view of a car containing my invention; Fig. 2 is a detail vertical sectional view taken on line D D Fig. 1 of the floor-supporting device; Fig. 3 is a vertical sectional view taken on line A A Fig. 2; Fig. 4 is a detail sectional view taken on line B B Fig. 1; and Fig. 5 is a vertical sectional view taken on line C C Fig. 4. Fig. 6 is an enlarged detail vertical sectional view illustrating the relative positions of the door and

floor member when the latter is in horizontal position.

The car body *b* and underframe *c* may be of any preferred construction presenting flanges *d* at each side of the floor openings and flanges *e* and *f* respectively at the ends of such openings, all these flanges extending inwardly relatively to their respective openings and being constructed and arranged to act as abutments limiting upward movement of the floor members.

The floor members, indicated at *g*, are hinged upon brackets *h* secured to the underframe near the flange *f* and the side edges thereof are offset downwardly as at *i*, while the main length of each member is straight to avoid presenting an obstacle to retard the flow of the lading as it is being discharged, the width of the offsets *i* being equal to the width of the flanges *d* for the purpose of presenting a flush floor, the object of this particular construction being to prevent the floor members being swung above horizontal position and to provide a grain tight flush floor.

The means for supporting the floor members in position constituting the hopper bottoms consists of diagonal angle iron sills *l* carried by webs *k* forming the side walls of the hoppers.

The means for supporting the floor members in horizontal position consists of slide bolts and doors *m*. The bolts are guided in cases *s* secured to the underframe of the car and the corners of the doors are cut away or notched to accommodate these cases which are adapted to act as closures for such notches when the doors are closed.

The doors *m* control the discharge from the hoppers when the floor members are in hopper bottom position and act as supports for such floor members when in horizontal position.

Each of these doors consists of a steel plate having its lower edge curved to substantially tubular form for the purpose of hinging the same upon a hinge rod *n* the ends of which are journaled in the side walls *k* of the hoppers, the tubular portion also acting as a stiffener for the plate. To present a seat for the free edge of its respective floor member when in horizontal position, each door is offset as at *w* in close proximity to its upper edge as indicated in Fig. 6, the upper edge of the door projecting slightly above the

floor member to engage the same when in this position, thus insuring that the door will be located with the shoulder formed by the offset in position to serve as a seat to 5 sustain the edge of the floor member. These doors are clamped in closed position by bars *o* provided with presser-feet *p* adapted to engage each door immediately beneath the offset therein. The bars *o* are operated by 10 handles *c* and when the doors are forced into position to support of the floor-members in horizontal floor position they supplement the bolts *p* and prevent the sagging of the doors between the bolts. In this manner the 15 floor-members are fully supported at all sides without the necessity of using extra heavy doors, as the bolts relieve them of considerable load.

To provide means for preventing leakage 20 of the lading through the hinges of the floor members and for cushioning the fall thereof when dropping from horizontal to hopper-bottom position the body plate of each member is extended in apron-like form as at *v* 25 and bent to a very slight angle and inserted beneath the flange *f* thus causing it to bear or rub upon this flange. The effect is that when the floor-members are lowered the apron-like part is sprung and offers the necessary yielding resistance to cushion the fall. 30

What I claim is as follows:—

1. In a convertible car the combination with a floor thereof having an opening therein and a pair of parallel hopper walls extending downwardly from the sides of the opening, of a hinged displaceable floor member forming in one position a part of the said floor and in another position a hopper floor, of means for supporting the said floor member in hopper-floor position and means for cushioning the fall of the floor member when dropping from the horizontal to the inclined position and for preventing leakage of the lading through the hinge of the floor member. 45

2. In a convertible car having a floor with an opening therein and parallel hopper walls extending downwardly from the sides of the opening, a flange secured to one side of the 50 said opening, a hinged displaceable floor member forming in one position a part of the said floor and in another position a hopper floor and an apron-like extension on the said floor member adapted to engage the said flange for cushioning the fall of the floor member when moving from the horizontal to the inclined position and preventing leakage of lading through the hinge. 55

3. In a car the combination with a downwardly movable normally horizontal hinged

floor-member, the pivot of the hinge of said floor member being located in a fixed position, said floor member serving as the floor of a discharge chute when lowered, a hinged member serving as an extension of the chute, 65 and means supporting the floor-member independently of the said last mentioned member.

4. In a car the combination with a downwardly movable normally horizontal hinged 70 floor-member, the pivot of the hinge of said floor member being located in a fixed position, said floor member serving as the floor of a discharge chute when lowered, a door hinged adjacent to the forward end of the 75 floor-member when in its lowermost position and serving as an extension of the chute, and means supporting the floor-member independently of the said last mentioned member.

5. A convertible car comprising the parts of a horizontal bottom car and hoppers beneath the level of such horizontal bottom, having displaceable floor members forming in one position a horizontal floor, and in another position floors for the hoppers, and means controlling the discharge from the hoppers and supporting the floor members in horizontal position and independent means for supporting the floor members in hopper 80 floor position. 85

6. A convertible car comprising the parts of a horizontal-bottom car and hoppers beneath the level of such horizontal bottom having displaceable floor-members forming 95 in one position a horizontal floor and in another position floors for the hoppers and doors hinged at the lower ends of the hoppers and controlling the discharge from the hoppers and supporting the floor-members in 100 horizontal position.

7. A convertible car comprising the parts of a horizontal bottom car and hoppers beneath the level of such horizontal bottom, having displaceable floor-members forming 105 in one position a horizontal floor and in another position floors for the hoppers, and manually operated strut-doors hinged at the lower ends of the hoppers and supporting the floor members in horizontal position, and 110 means mounted independently of and for locking the strut-doors in floor-supporting position.

In testimony whereof I have signed my name to this specification in the presence of 115 two witnesses.

RICHARD WEBB BURNETT.
